UNITED STATES PATENT OFFICE.

CHARLES BAXTER, OF WAUKESHA, WISCONSIN.

WIRE-FENCE SPACER.

SPECIFICATION forming part of Letters Patent No. 606,182, dated June 28, 1898.

Application filed August 9, 1897. Serial No. 647,548. (No model.)

To all whom it may concern:

Be it known that I, CHARLES BAXTER, a citizen of the United States, residing at Waukesha, in the county of Waukesha and State 5 of Wisconsin, have invented new and useful Improvements in Wire-Fence Spacers, of which the following is a specification.

My invention relates to improvements in that class of wire-fence spacers used in weaving stays, where it is desirable that the line-wires be kept at uniform distance from each other prior to the application of the stays thereto.

The spacers in common use are adapted to 15 be used on smooth wire only, in that the line-wires are engaged by hooks or loops which are operated by thumb-screws, and they cannot be readily applied to or removed from the wire, but are intended to be slipped along the 20 wire from place to place as the stay-wires are woven. Where the line-wires are barbed, therefore, these spacers cannot be used practically, as the spacer will not slide along such wire, and each line-wire has to be separately 25 disengaged from the spacer by turning the thumb-screw to loosen the wire-holding hook or loop and release the wire.

The object of my invention is to provide a 30 form of spacer from which the line-wires may be readily engaged or disengaged, so that the spacer may be removed and replaced almost as quickly as it may be slipped along the wire without removal.

In the following description reference is had 35 to the accompanying drawings, in which—

Figure 1 is a side view of my invention as it engages the line-wires of a fence. Fig. 2 is a detail view of the central portion of the bars, showing the actuating-lever and also 40 showing the prongs in a separated position, adapted to release the fence-wires, with dotted lines indicating the closed position. Fig. 3 is a side view showing a modified form of construction in which the bars are composed 45 of metal. Fig. 4 is an edge view as seen from the opposite side of the fence from that occupied by the operator.

Like parts are identified by the same reference-letters throughout the several views.

50 Two parallel bars A and A' are held together by bolts B and nuts C, the bar A be-

ing provided with slots D to permit a longitudinal movement. The rear edge of the bar A is also provided with a recess E, in which is located a lever F, pivoted at G to the bar 55 A' and adapted by the engagement of its short end against the upper end E' of the recess E to raise the bar A upon the bar A'. When the lever is turned into a vertical position, it tends to so remain and hold the bar A in its 60 raised position.

The front edges of the bars A and A' are provided with prongs H and H', respectively, the prongs H of the bar A being upwardly inclined and the prongs H' of the bar A' being downwardly inclined and adapted to engage the line-wire between them when the bar A is in its raised position. These prongs may be formed of metal and driven into the edges of the wooden bars, or the bars themselves 70 may, if desired, be formed of metal and recessed along their edges to form the prongs, as shown in Fig. 3.

In the drawings I have shown the prongs arranged at distances of one inch apart, with 75 space-marks upon the bars and the foot-marks indicated by numerals, so that the same device may be used for spacing wires at any desired distance from each other from one inch to one foot or more.

It is obvious that by means of the lever F the prongs can be made to instantly engage or release the wire, and the spacer may be shifted by removal and replacement almost as quickly as by slipping it along the wire 85 without such removal.

Having thus described my invention, what I claim as new, and desire to secure by Letters Patent, is—

1. A wire-fence spacer comprising the parallel bars, adjustably secured together and provided with wire-engaging prongs, and a lever pivotally secured to one of the bars and operating in a recess in the other bar, whereby, when said lever is turned to a vertical position, the recessed bar will be lifted upon the other to adjust the prongs in a position for engaging the fence-wires, and the lever locked in such position by reason of the bearing of the recessed bar upon the end of the 95 lever above its pivotal support, substantially as described.

2. A wire-fence spacer comprising the parallel wooden bars adjustably secured together and provided with metallic wire-engaging prongs, together with a lever pivoted 5 to one of the bars and operating in a recess in the other bar, whereby when said lever is adjusted in a vertical position, it is adapted to become locked by the bearing of the re-

cessed bar upon its end above its pivotal support, substantially as described.

In testimony whereof I affix my signature in the presence of two witnesses.

CHARLES BAXTER.
